UNITED STATES PATENT OFFICE

JAMES SHELDON CARTWRIGHT AND THOMAS DAVEY, OF WINTHROP, MASSACHUSETTS

CLUTCH

Application filed June 7, 1928. Serial No. 283,536.

This invention relates to clutches and has for its object the production of a simple but effective device of this character which may be applied readily to a sewing machine actuated by an electric motor.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

20 Of the drawings:

Figure 1 represents a vertical section of a clutch embodying the principles of the present invention and showing in elevation a portion of a sewing machine and the motor for driving same.

Figure 2 represents a section of same on line 2, 2, on Fig. 1.

Figure 3 represents a plan of the expanding ring and a portion of the hub on which it is mounted.

Figure 4 represents a section on line 4, 4, on Fig. 3, and

Figure 5 represents a vertical section on line 5, 5, on Fig. 1.

Similar characters indicate like parts throughout the several figures of the drawings.

In the drawings, 10 is a portion of the frame of a machine from which extends the driving shaft 11 thereof.

This frame 10 is provided with a bracket 12 on the outer end of which is mounted an electric motor 13 which may be of any well known construction.

The motor 13 is provided with a driving shaft 14 in alinement with the shaft 11, of the machine to be operated.

Secured to the driving shaft 14 is a collar 15 having pins 16 extending therefrom into

openings 16* in a disk 17 which is slidably mounted on the shaft 14.

The hub of this disk 17 has an annular groove 18 in the periphery thereof into which project the trunnions 19 of a lever 20 pivoted at 21 to the bracket 12.

The lever 20 has an arm 22 adjustably mounted thereon and clamped thereto in adjusted position by a bolt 23.

This arm 22 has a rearwardly extending bar 24 secured thereto by a pin 25, the outer end of said bar being pivoted by pin 26 to a lever-actuating rod 27, the lower end of which is connected to any suitable operating device such as a treadle.

As the treadle forms no part of the present invention it is not considered necessary to illustrate the same.

A spring 28 between the arm 22 and bracket 12 normally retains the disk 17 in the position shown in Fig. 1.

When the motor 13 is in operation the driving shaft 14 thereof will impart rotary movement to the reciprocating disk 17 by means of the members 16 positioned in the openings 16* in the hub of said disk.

One face of the disk 17 is provided with a recess 28* in the bottom of which is disposed a sheet 29 of cork or some similar material.

The shaft 11 has secured thereto a flywheel 30 the hub 31 of which is cone-shaped with its outer end extending into the recess 28* of disk 29.

A plate 32 is secured to the hub 31 by means of screws 33 having heads 34 adapted for reciprocation in depressions 35 in said hub 31.

This plate 32 has limited movement towards and from the outer end of hub 31 and under normal conditions is retained in a position slightly separated from the cork sheet 29 by means of a spring 36, as shown in Fig. 1.

When in this position the motor 13 may be driven without imparting any rotary movement to the shaft 11.

The plate 32 has an annular flange 37 extending into an annular groove 38 in a split ring 39 surrounding the hub 31 of flywheel 30.

The width of the groove 38 is greater than 100

the thickness of the flange 37 thereby permitting the expansion of the split ring 39.

5 The inner face of this ring is tapered to conform to the cone-shaped periphery of the hub 31 which has extending therefrom a wedge-shaped projection 40, the opposite faces of which contact with the adjacent ends of the split ring 39.

10 When the split ring 39 is forced toward the flywheel 30 the inclined faces of the wedge 40 will expand the ring slightly so that the periphery thereof will be brought into frictional contact with the inner cylindrical wall of the recess 28.

15 When the frictional contact is sufficient to bind the ring 39 and disk 17 together the full speed of the motor shaft 14 will be imparted to the driving shaft 11 of the machine.

20 Radial pins 41 in the split ring 39 extend through slots 42 in the flange 37 to tie the ring and plate 32 together while permitting the expansion of said ring 39.

25 The ring 39 is made of spring metal and will return to its normal position when again moved outwardly on the hub 31.

30 The outer end of the arm 22 has an opening 43 extending therethrough in which is disposed the projection 44 of a plate 45 having friction disks 46 secured thereto in depressions 47 at opposite ends thereof.

35 A headed stud 48 secures a washer 49 to the outer end of the projection 44 which washer extends beneath the arm 22 and is separated therefrom slightly so that said plate 45 may rock upon said arm 22.

40 The friction pads 46 are disposed beneath the flywheel 30 and are forced into frictional contact with the periphery thereof by means of the spring 28 when the clutch parts are disengaged.

45 When the lever 20 is moved to the left in Fig. 1 to engage the clutch parts the same movement will move the pads 46 free from contact with said wheel 30.

50 The rocking movement of the plate 45 is provided to insure both pads 46 always contacting with the flywheel 30 when it is desired to retard and stop the rotating of said wheel.

55 With the parts in the position indicated in Fig. 1 of the drawings, the motor 13 can rotate without imparting any rotary movement to the driving shaft 11 but as soon as the operator actuates the treadle to move the upper end of the lever 22 towards the left, the friction pads 46 will be removed from the periphery of the flywheel 30 and the cork sheet 29 will be forced into contact with the plate 32 within the recess 28 of the disk 17.

60 This frictional contact between the cork sheet 29 and the plate 32 will cause the split ring to be slowly rotated about the axis of the shaft 11, this rotation being transmitted through the wedged member 40 to the hub of the flywheel thereby causing the latter to ro-

tate and transmit a slow rotary movement to said shaft 11.

65 The continued movement of the lever 20 to the left will force the split ring toward the flywheel 30 and owing to the wedged shape of the projection 40 this ring 39 will be expanded until its periphery comes into contact with the cylindrical wall of the recess 28 formed in the disk 17.

70 Further movement of the ring 39 to the left of Fig. 1 will cause it to be firmly locked between the cone-shaped hub 31 of the flywheel 30 and said cylindrical wall so that the disk 17, the flywheel 30, and driving shaft 11 will rotate at the same speed as that of the 75 shaft 14 of the motor 13.

75 As soon as the operator removes his foot from the treadle the spring 28 will cause the lever 20 to move clockwise about its pivot 21, thereby moving the disk 17 to the right and 80 permitting the spring 36 to move the plate 32 to its normal position as indicated in Fig. 1, at which time the spring of the metal in the split ring 39 will cause it to be removed from contact with the cylindrical wall of the 85 recess 28.

90 While the clutch parts are being disengaged in the manner just described, the friction pads 46 will be moved into contact with the periphery of the flywheel 30 to retard 95 further movement of said flywheel and then prevent all rotation thereof.

95 It is believed that the operation and many advantages of the invention will be understood without further description.

100 Having thus described our invention, we claim:—

1. The combination of two alined shafts; a flywheel on one shaft provided with a cone-shaped hub; a motor to drive the other shaft; 105 a disk slidable on and rotatable with the motor shaft and provided with a cylindrical recess in one face thereof; a split ring fitted to and rotatable with said hub and disposed in said recess, said ring having an annular groove in its outer face; a plate revoluble with said hub having a flange extending into said groove; and a wedge member on said hub between the ends of said ring adapted to expand said ring when moved inwardly on said 110 hub.

115 2. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess, said ring having an annular groove in its outer face; a plate revoluble with said hub having a flange extending into said groove; means for limiting the outward movement of said plate to prevent contact under normal conditions with the bottom of said recess; and a wedge member on 120

said hub between the ends of said ring adapted to expand said ring when moved inwardly on said hub.

3. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess, said ring having an annular groove in its outer face; a plate revoluble with said hub having a flange extending into said groove; two screws secured to said plate and reciprocable in said hub and provided with heads to limit the outward movement of the plate; and a wedge member on said hub between the ends of said ring adapted to expand said ring when moved inwardly on said hub.

4. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess, said ring having an annular groove in its outer face; a plate rotatable with said hub having a flange extending into said groove, said flange having a thickness less than the width of said groove to permit the expansion of the split ring; and a wedge member on said hub between the ends of said ring adapted to expand said ring when moved inwardly on said hub.

5. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess, said ring having an annular groove in its outer face; a plate rotatable with said hub having a flange extending into said groove, said flange having a thickness less than the width of said groove to permit the expansion of the split ring; radial pins in said ring extending through slots in said flange; and a wedge member on said hub between the ends of said ring adapted to expand said ring when moved inwardly on said hub.

6. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess, said ring having an annular groove in its outer face; a plate revoluble with said hub having a flange extending into said groove; a spring between said hub and plate to force the plate outwardly; means for

limiting the outward movement of said plate; and a wedge member on said hub between the ends of said ring adapted to expand said ring when moved inwardly on said hub.

7. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess, said ring having an annular groove in its outer face; a plate revoluble with said hub having a flange extending into said groove; a sheet of resilient material in the bottom of said recess normally free from contact with said plate; and a wedge member on said hub between the ends of said ring adapted to expand said ring when moved inwardly on said hub.

8. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess; means for moving said disk endwise and expanding said ring into frictional contact with the cylindrical wall of said recess; and a brake member operable by said moving means coating with said flywheel when the clutch parts are disengaged.

9. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess; and means for moving said disk endwise and first imparting slow rotation to said hub and then expanding said ring into frictional contact with the cylindrical wall of said recess to rotate the flywheel at full speed.

10. The combination of two alined shafts; a flywheel on one shaft provided with a cone-shaped hub; a motor to drive the other shaft; a disk slidable on and rotatable with the motor shaft and provided with a cylindrical recess in one face thereof; a split ring fitted to and rotatable with said hub and disposed in said recess, said ring being normally free from contact with said disk; and means for moving said disk endwise and first imparting slow rotation to said hub and then expanding said ring into frictional contact with the cylindrical wall of said recess to rotate the flywheel at full speed.

11. The combination of two alined shafts; a flywheel on one shaft provided with a cone-shaped hub; a motor to drive the other shaft; a disk slidable on and rotatable with the motor shaft and provided with a cylindrical

recess in one face thereof; a split ring fitted to and rotatable with said hub and disposed in said recess; and means for moving said disk endwise of said motor shaft and expanding said ring into frictional contact with the cylindrical wall of said recess.

12. The combination of two alined shafts; a flywheel on one shaft provided with a cone-shaped hub; a motor to drive the other shaft;

10 a disk slideable on and rotatable with the motor shaft and provided with a cylindrical recess in one face thereof; a split ring fitted to and rotatable with said hub and disposed in said recess, said ring being normally free

15 from contact with said disk; and means for moving said disk endwise of said motor and expanding said ring into frictional contact with the cylindrical wall of said recess.

13. The combination of two alined shafts; a member on one shaft provided with a cone-shaped hub; a motor to drive the other shaft;

20 another member rotatable with the motor shaft and provided with a cylindrical recess in one face thereof; a split ring fitted to and rotatable with said hub and disposed in said recess; and means for moving one member

25 endwise of the shaft on which it is mounted and expanding said ring into frictional contact with the cylindrical wall of said recess.

30 Signed by us at 746 Old South Building, Boston, Massachusetts, this 5th day of June, 1928.

JAMES S. CARTWRIGHT.
